UNITED STATES PATENT OFFICE.

JOSEPH H. BRISKIN, OF LOS ANGELES, CALIFORNIA, ASSIGNOR TO AERO RADIATOR MFG. CO., OF LOS ANGELES, CALIFORNIA, A PARTNERSHIP CONSISTING OF JOSEPH H. BRISKIN AND FRANK MEYER.

RADIATOR CONSTRUCTION.

Application filed April 2, 1924. Serial No. 703,637.

To all whom it may concern:

Be it known that I, JOSEPH H. BRISKIN, a citizen of the United States, residing at Los Angeles, in the county of Los Angeles and State of California, have invented new and useful Improvements in Radiator Constructions, of which the following is a specification.

My invention relates to radiator core construction and consists of the novel features herein shown, described and claimed.

An object of my invention is to make a radiator core construction in which each water tube is formed of two pieces of thin metal having plain zig-zag bends, the metal of the two pieces fitting closely together along their side margins and the metal of the two pieces being oppositely bulged outwardly between the close fitting margins to form the water space.

Another object is to space the water tubes with a single sheet of metal having margins fitting the margins of the water tubes and the spacer being formed of very thin metal transversely cut in places and having main zig-zag bends corresponding to the zig-zag bends of the water tubes and having small reverse bends parallel with the main bends and extending between the transverse cuts so as to form sheets in which the edges of the water tubes will fit and so as to form the greatest practical amount of opposing lines to produce stiffness of the spacing piece to resist collapsing of the water tubes towards each other, the transverse cuts producing round edges or fins to serve as flanges for stiffening the edges along the cuts and to make a resistance to the air.

Other objects and advantages will appear from the drawings and specifications.

The drawings illustrate the invention.

Figure 1 is a top plan view of two tubes formed and assembled in accordance with the principles of my invention and including two spacers, the view being taken looking in the direction indicated by the arrows 1 in Figs. 2 and 3.

Fig. 2 is an edge view looking in the direction indicated by the arrow 2 in Fig. 1.

Fig. 3 is a vertical cross section on a plane

parallel with Fig. 2 and on the lines 3—3 of Figs. 1 and 4.

Fig. 4 is a horizontal section on the lines 4—4 of Figs. 2 and 3.

Fig. 5 is a fragmentary plan perspective 55 of the spacer and taken looking in the direction indicated by the arrow 5 in Fig. 6.

Fig. 6 is an edge view looking in the direction indicated by the arrow 6 in Fig. 5.

Fig. 7 is a cross section on the line 7—7 60 of Fig. 5 and on a plane parallel with Fig. 6.

Fig. 8 is a cross section on the line 8—8 of Fig. 5 and on a plane parallel with Fig. 6.

Fig. 9 is a sectional detail longitudinal of the bends and crimps as indicated by the 65 line 9—9 of Fig. 5.

Fig. 10 is a view analogous to Fig. 9 and taken on the line 10—10 of Fig. 5.

Fig. 11 is a fragmentary plan of a water tube plate as seen looking in the direction 70 indicated by the arrow 11 in Fig. 12.

Fig. 12 is an edge view as indicated by the arrow 12 in Fig. 11.

Fig. 13 is a sectional detail on a plane parallel with the zig-zag bends and as indicated by the lines 13—13 in Fig. 11. 75

Fig. 14 is a fragmentary sectional detail on a plane parallel with the zig-zag bends and showing how the margins of two water tube plates fit together and how the plates 80 are bulged outwardly between the margins to form the water space.

The details of the radiator core construction shown in the drawings are as follows:

Referring to Figs. 11, 12, 13 and 14, the 85 water tube plate 1 is long enough to make one side of a water tube having zig-zag bends and extending from the bottom of a radiator to the top. The side margins 2 and 3 of the plate are smoothly and evenly 90 bent zig-zag so that the margin of one plate will fit closely against the margin of the other plate. The figures show the construction upon an enlarged scale. The intermediate portion 4 between the margins 2 and 3 95 is bulged in one direction thruout the plate so that when two plates are placed together with the bulging portions 4 outward a water space 5 is formed. In forming the zig-zag bends, alternate bends 6 are formed to pro- 100

duce sharp straight edges and the other bends 7 are rounded so that when the two plates are placed together to form a water tube all of the outwardly extending bends 5 are the sharp bends 6 and these sharp bends 6 are adapted to assist in assembling the water tubes relative to the spacer. The sharp bends 6 extend only from margin to margin.

- 10 Referring to Figs. 6, 7, 8, 9 and 10, which are drawn upon a greatly enlarged scale, the spacer plate 8 is formed of very thin sheet metal of the same width as the water tube plate 1 and has margins 9 and 10 bent 15 smoothly zig-zag to match the bends of the water tube plate and adapted to fit against the margins of the water tube plates in spots 11 and 12. A small groove 13 extends from the spot 11 of one margin to the spot 11 of 20 the other margin, and in forming the grooves the metal is reversely bent on lines parallel with the other bends. A similar groove 14 extends from the spot 12 of one margin 10 to the spot 12 of the other margin 25 9 and is formed by reversely bending the metal.

In the line of the groove 13 transverse cuts 14^a and 15 are formed and the metal between the cuts is reversely bent in the 30 same direction as the reverse bend of the groove 13 upon a much larger scale and in forming the cuts 14^a and 15 which are simply slit, the edges 16 and 17 are bent laterally and form flanges transverse of the other 35 bends to serve as braces for the adjacent metal and to resist the passage of air and increase the radiating surface.

In the line of the groove 14 and near one 40 end, are the transverse cuts 18 and 19 and near the other end are transverse cuts 20 and 21 and the metal between the cuts 18 and 19 and 20 and 21 is reversely bent upon a greatly enlarged scale relative to the groove 14 to form the portions 22 and 23. 45 Depressions 24 and 25 are formed in the walls of the portion 22 and similar depressions 26 and 27 are formed in the walls of the portion 23 to still further complicate the bends and stiffen the construction. The 50 metal along the edges of the slits 18, 19, 20 and 21 is drawn laterally to make the flanges 28 and 29 serve the same purpose as the flanges 16 and 17. All of the conflicting 55 bends and flanges serve to stiffen the separator plate and are repeated over and over in forming the completed plate of which Fig. 5 is a fragment.

Referring to the cross section assembly in 60 Fig. 3, the water tube plates 1 are placed together with the bulging portions 4 extending outwardly, thus producing the water passage 5 and the separator plate 8 is placed in position with the sharp bends 6 of one side of the water tube entering the grooves 65 13 of the spacer and the next water tube

plate 1 is placed in position with the sharp bends 6 in the grooves 14. The construction of the spaces 8 when assembled in this way is especially adapted to resist crushing or the movement of the water tube on one side 70 of the spacer towards the water tube on the other side of the spacer.

The upper ends of the plates 1 of two adjacent water tubes are seamed together and produce the folded ridge 30. A similar 75 fold may be formed at the other ends of the water tubes. In a like manner a second spacer 8 is placed in position with the sharp bends 6 in the grooves 13 and 14 and the upper ends of the plates 1 folded together 80 to produce another ridge 30, and in this manner a radiator core may be built up to any desired size and shape and after the parts are properly assembled, cleaned and treated with flux, the entire core may be 85 submerged in hot solder or the like, and all of the parts fitting against each other will be soldered together. The water passages 5 will be open at the top and bottom and the air passages on both sides of the spaced 90 plates will be open at the front and back, so that the water may flow upwardly through the water passages and the air may flow from front to back around the spacer plates and against the outer surfaces of the 95 water tubes, the construction serving especially well to absorb the heat from the water tubes and carry the heat away with the air.

Various changes may be made without departing from the spirit of my invention 100 as claimed.

I claim:

1. In a radiator core construction the combination with two zig-zag water tubes having smooth zig-zag margins of a spacer 105 plate bent zig-zag and having smooth spots at the ends of its outer corners to fit the margins of the water tubes and having portions of the metal between the spots reversely bent to form small grooves to receive 110 the outer corners of the zig-zag tubes and having slits across the grooves, the metal between the slits being reversely bent upon a larger scale than the reverse bends forming the grooves and there being depressions 115 in the walls of the portions between the slits.

2. In a radiator core construction the combination with two zig-zag water tubes having smooth zig-zag margins of a spacer 120 plate bent zig-zag and having smooth spots at the ends of its outer corners to fit the margins of the water tubes and having portions of the metal between the spots reversely bent to form small grooves to receive 125 the outer corners of the zig-zag tubes and having slits across the grooves, the metal between the slits being reversely bent upon a larger scale than the reverse bends forming the grooves, the metal at the sides 130

of the slits being drawn laterally to form flanges serving as transverse braces.

3. In a core construction a spacer plate bent zig-zag and having small reverse bends parallel with the lines of the zig-zag bends and having slits crosswise of the reverse ends, the portions between the slits being bent more than the reverse bends and having

the edges of the slits drawn laterally to form braces and having portions depressed so as to make a multiplicity of bends, reverse bends, transverse slits and transverse braces to stiffen the spacer.

In testimony whereof I have signed my name to this specification.

JOSEPH H. BRISKIN.
